UNITED STATES PATENT OFFICE.

HENRY F. SCHMIDT, OF SWARTHMORE, PENNSYLVANIA, ASSIGNOR TO WESTINGHOUSE ELECTRIC AND MANUFACTURING COMPANY, A CORPORATION OF PENNSYLVANIA.

FLUID TRANSLATING DEVICE.

1,421,840.

Specification of Letters Patent.

Patented July 4, 1922.

Original application filed September 14, 1914, Serial No. 861,633. Divided and this application filed April 16, 1920. Serial No. 374,371.

To all whom it may concern:

Be it known that I, HENRY F. SCHMIDT, a citizen of the United States, and a resident of Swarthmore, in the county of Delaware and State of Pennsylvania, have invented a new and useful Improvement in Fluid-Translating Devices, of which the following is a specification, this application being a division of my application Serial No. 10 861,633, filed Sept. 14, 1914.

This invention relates to fluid translating devices and particularly to ejector apparatus for maintaining a high vacuum in condensers or similar apparatus.

15 An object of the invention is to produce a fluid ejecting device of the kinetic type in which new and improved means are employed for maintaining the operation of the device substantially constant for practically all varying conditions.

20 These and other objects are attained by means of apparatus embodying the features herein described and illustrated in the drawings accompanying and forming a part 25 of this application.

In the drawings the single figure is a diagrammatic sectional view of air ejector embodying my invention.

The ejector illustrated consists essentially 30 of a diffuser 2 of any desired form, a mixing chamber 3, and a plurality of motive fluid delivery nozzles, located in the mixing chamber and movable toward and away from the inlet of the diffuser for the purpose 35 of stabilizing the operation of the ejector under varying operating conditions, or under varying conditions of flow of the medium to be expelled. In the apparatus illustrated the automatic means are employed 40 for varying the position of the nozzles with relation to the diffuser in response to variations in pressure conditions within the ejector.

In the drawings, I have illustrated an arrangement 45 of nozzles, which includes a main motive fluid delivery nozzle 4 and a plurality of accelerating nozzles 5, which also deliver motive or expelling fluid into and through the diffuser 2. As shown, the nozzle 4, is located axially of the diffuser and is movable axially toward and away from the diffuser, whereas the accelerating nozzles movable with the main nozzle are located between the main nozzle and the

diffuser are arranged in an annular series. The nozzles 5 are inclined inwardly at their discharge ends and are so located with relation to the main nozzle 4 that the jets of fluid discharged by them combine with the jet delivered by the nozzle 4 and produce in effect a single jet which passes into and through the diffuser.

As shown, the main nozzle 4 is mounted on a movable head 6, which in effect forms a steam chamber for all the nozzles, and communicates with the motive fluid inlet pipe 7 of the ejector through a conduit 8 which is telescopically connected to the pipe 7. The head is shown provided with an extension or cage 6^a on which the nozzles 5 are mounted. The cage is so formed that it not only delivers motive fluid to the nozzles 5 but also provides adequate means for delivering medium to be ejected or expelled, to the nozzle 4, so that the entraining action of the stream of motive fluid delivered from that nozzle is not nullified or minimized by the shrouding effect of the nozzles 5 and the motive fluid delivered by them. This is accomplished by providing ports 9 in the cage 6^a which are of sufficient size to permit of an adequate flow of medium to be expelled into the cage, so that the entraining action of the nozzles 4 and 5 is maintained at a maximum for all varying conditions encountered.

The combined nozzle is capable of moving automatically toward or from the throat of the diffuser 2 in response to variations in the amount of medium entering the combining chamber 3 through the port 11. As illustrated, the conduit 8 extends upwardly through the top of the combining chamber 3, and has secured thereto a plunger 12 mounted in a cylinder 14, which may be formed integrally with the combining chamber 3. The space within the cylinder 14 above the plunger 12 communicates with the throat of the diffuser 2 through a passage 15, and the space below the plunger 12 communicates with the chamber 3 through an annular passage 16 surrounding the conduit 8. A spring 17 may be also provided within the lower portion of the cylinder 14, so arranged as to exert an upward pressure upon the plunger 12. The area of the plunger 12 and the strength of the spring 17 are so proportioned that the combined nozzle moves to such positions, in response

to the pressure within the chamber 3, that the medium from the chamber 3 is always just sufficient to fill the gap between the nozzle and the inlet of the diffuser.

5 The operation of the apparatus is as follows:

Under normal pressure conditions within the chamber 3, the combined nozzle occupies a position approximately as shown in the 10 drawing, and both the accelerating nozzles 5 and the main nozzle 4 are effective in entraining and moving the medium from the chamber 3 through the diffuser. As the pressure of the chamber 3 decreases, 15 the combined nozzle moves toward the throat of the diffuser, and, at some predetermined pressure, as when there is little or no medium within the chamber 3 to be expelled, the combined nozzle moves to 20 such position as to close the gap between it and the diffuser. Under such conditions the fluid discharged from the accelerating nozzles acts only as a filler for the diffuser 2, and the nozzle 4 is alone effective in maintaining 25 a low absolute pressure within the chamber 3. As the pressure within the chamber 3 increases, the combined nozzle moves away from the throat of the diffuser and assumes a position such that for any 30 pressure within the chamber 3, the medium passing therefrom is always just sufficient to fill the gap between the nozzle and the inlet of the diffuser.

While I have shown my invention in but 35 one form, it will be obvious to those skilled in the art that it is not so limited but is susceptible of various other changes and modifications, without departing from the spirit thereof and I desire, therefore, that 40 only such limitations shall be placed thereupon as are imposed by the prior art or as are specifically set forth in the appended claims.

What I claim is:—

45 1. In combination, a chamber for fluid to be translated, a diffuser communicating there-

with, and a series of motive fluid nozzles movable to different positions relatively to the diffuser, and means responsive to the amount of fluid in said chamber for varying 50 the effective passage area for fluid to be translated.

2. An ejector comprising a chamber, a diffuser communicating therewith, an element having a series of nozzles for delivering motive fluid through the diffuser for translating medium contained in the chamber, said element being movable toward and from the inlet of the diffuser to vary the effective inlet area of the latter, and means 55 responsive to the variations in the pressure of medium to be translated for varying the effective inlet area of the diffuser.

3. An ejector comprising a mixing chamber having an inlet for fluid to be translated, 60 a diffuser communicating with the mixing chamber, a nozzle head cooperative with the inlet of the diffuser to vary the inlet of the diffuser, means responsive to the pressure of fluid in the mixing chamber to move 70 the nozzle head to vary the inlet area, said nozzle head having a central diffusing nozzle and an annular series of converging diffusing nozzles surrounding and below the central diffusing nozzle, and said head also 75 having ports for fluid to be translated cooperative with the central diffusing nozzle.

4. An ejector comprising a chamber for fluid to be translated, a diffuser communicating therewith, a nozzle head within the 80 chamber having a main motive fluid nozzle and a series of accelerating nozzles located therebelow, a means responsive to the amount of fluid to be translated in said chamber for varying the entraining capacity of the 85 accelerating nozzles.

In testimony whereof, I have hereunto subscribed my name this day of March 30, 1920.

HENRY F. SCHMIDT.

Witness:

C. W. McGHEE.
